UNITED STATES PATENT OFFICE.

ISAAC N. HEATWOLE, OF DALTON, OHIO.

GARMENT FASTENER.

1,405,688.

Specification of Letters Patent.

Patented Feb. 7, 1922.

Application filed March 5, 1921. Serial No. 449,874.

To all whom it may concern:

Be it known that I, ISAAC N. HEATWOLE, a citizen of the United States, residing at Dalton, in the county of Wayne and State 5 of Ohio, have invented a new and useful Garment Fastener, of which the following is a specification.

This invention relates to garment fasteners and more particularly to a fastener of 10 the hook and eye type, and the objects of the invention are to provide a garment fastener of this character which is adapted for connecting adjacent sections of a garment in such a manner as to preclude the possibility 15 of accidental displacement or unfastening thereof, while at the same time the fastener may be easily and readily unfastened or opened when desired.

The above together with other objects are 20 attained by providing a fastener formed of two members, one member provided with an eye adapted to be connected to one section of a garment and the other member provided with a hook arranged to be inserted 25 into the eye, said hook being so formed that it cannot be removed from the eye without turning the same approximately at right angles to its normal position, thus preventing accidental opening of the fastener.

30 In the accompanying drawings forming part hereof,—

Figure 1 is a front elevation of a garment fastener embodying the invention showing the same applied to adjacent sections of a 35 garment or the like.

Fig. 2 is a section on an enlarged scale taken upon the line 2—2, Fig. 1.

Fig. 3 is a section on an enlarged scale taken upon the line 3—3, Fig. 1.

40 Fig. 4 is a rear elevation of the eye member of the fastener.

Fig. 5 is a perspective view of the hook member.

Fig. 6, an end elevation of the same, and

45 Fig. 7, a section on the line 7—7, Fig. 4.

Similar numerals of reference indicate corresponding parts throughout the several figures of the drawing.

50 Adjacent sections of a garment are represented by the numerals 1 and 2, the section 2 overlapping the section 1 as is common in coats and similar garments.

It will be understood that this fastener is especially adaptable for use upon heavy 55 outer coats of moleskin, corduroy and the like and is designed to take the place of the

usual "arctic" fasteners such as are commonly used upon coats of this character.

The hook member is designed to be attached to the edge portion of the section 2 60 of the garment and comprises the supporting plate 3, formed of sheet metal and bent upon itself as best shown in Fig. 3.

The hook 4, which is formed of wire or the like, of suitable size, is extended through 65 an aperture 5 in the folded edge of the attaching plate, the inner extremity thereof forming an eye 6 which is located around the adjacent attaching rivet 7, these rivets being preferably provided for attaching the 70 plate to the garment.

The outer end of the hook 4 is provided with the hook proper 8, said hook portion being bent inwardly toward the garment at an angle, as well as downwardly as indicated 75 at 9, the free extremity thereof extending outwardly away from the garment as well as upwardly at an angle as shown at 10.

The eye member comprises the sheet metal plate 11, the edge portion thereof being bent 80 over a somewhat similar plate 12, as shown at 13, for the purpose of connecting the two plates together, the forward edges of these two plates, however, not being connected together.

85 The outer plate 11 is provided with an opening 14 arranged to receive the hook, the inner plate 12 being provided with a depression 15 registering with said aperture, forming a chamber through which the hook 90 is passed. The eye member may be attached to the garment by means of the rivets 16 as shown.

In attaching the hook member to the eye member in order to close the garment or 95 other article upon which the fastener is carried, it is necessary to turn the upper end of the supporting plate of the hook member outwardly away from the garment upon the shank 4 of the hook as an axis, into a position 100 approximately at right angles to the normal position of the hook member. The free extremity 10 of the hook is then inserted into the opening 14 in the eye member and the hook member is turned back to the normal 105 position, thus fastening the members together as shown in Fig. 1.

In order to unfasten the device it is necessary to again turn the supporting plate of the hook member outwardly away from the garment at right angles before the hook can be disengaged from the eye member. It will,

of course, be understood that instead of turning the upper end of the supporting plate of the hook member outwardly as described, in order to fasten or unfasten the device, the upper end of the supporting plate of the eye member may be turned inwardly to the same extent, or each member may be given a partial turn in opposite directions in order to allow the hook to be inserted in 10 or disengaged from the eye.

With this construction it will be seen that the possibility of the fastener becoming accidentally opened is reduced to a minimum, as there will be little probability of the 15 garment being accidentally moved into such position as to allow the hook to become disengaged from the eye.

The chamber formed by the depression 15 in the rear plate 12 of the eye member 20 is of sufficient depth to allow free movement of the hook therethrough in fastening or unfastening the device as above described,

but is sufficiently shallow to prevent the hook from being disengaged from the eye until the entire hook member is turned as 25 above described.

I claim:—

A separable fastener including an eye member and a hook member, the hook member having a hook located at an angle to 30 the normal plane of the eye member and arranged to be twisted upon the axis of the hook in order to insert the same in the eye member, or release the same therefrom, the eye member comprising two spaced sheets 35 of metal, the outer sheet having an aperture spaced from the edge, the inner sheet having an open ended chamber therein communicating with said aperture and adapted to receive the hook.

In testimony that I claim the above, I have hereunto subscribed my name.

ISAAC N. HEATWOLE.
